D 6692

357

UNITED STATES PATENT OFFICE.

JOSEPH PECKOVER, OF CINCINNATI, OHIO.

DESIGN FOR A COOKING-STOVE.

Specification forming part of Design No. 6,692, dated May 27, 1873; application filed February 27, 1873.

To all whom it may concern:

Be it known that I, JOSEPH PECKOVER, of Cincinnati, in the county of Hamilton and State of Ohio, have invented a Design for Stoves, of which the following is a specification:

The nature of my design is fully represented in the accompanying engraving, to which reference is made.

My stove is designed to be used as a parlor cook-stove, and to be so ornamented as to serve either the purpose of a heating or a cook stove or both.

The characteristic features of a stove embodying my design are, the elevated fire-box projecting over the hearth and having a front that recedes toward the hearth, a large base-chamber under said hearth serving partly as a receptacle for ashes and partly as an oven, and of stove-back which descends from the top in a vertical line a short distance, then inclining rearward continues vertically to the base in a plane further removed from the front than the plane of the upper portion, thus giving a greater depth below from front to rear

than above the hearth, without impairing the symmetry of the design.

In the drawing, A is the elevated overhanging fire-box; B, the receding part of the front. C is the hearth. D is the base-chamber extending out under the hearth. F G are the upper part of the stove-back. G H are the rearward inclined part of the back, and H I are the lower portion of the back.

I am aware that ornamented parlor cook-stoves having elongated arms are not new.

The distinctive feature of my design is found in the overhanging front occasioned by the situation of the fire-box.

What I claim is—

1. The design in a parlor cook-stove of the front A B, substantially as described.
2. The design for a cook-stove of the front A B, hearth C, base-chamber D, and back F G H I, substantially as described.

JOSEPH PECKOVER.
